UNITED STATES PATENT OFFICE

ERNEST C. PILGRIM, OF OKMULGEE, OKLAHOMA, ASSIGNOR TO THE JENSEN-SALSBERRY LABORATORIES, INC., OF KANSAS CITY, MISSOURI, A CORPORATION OF MISSOURI

SURGICAL INSTRUMENT

Application filed November 2, 1931. Serial No. 572,512.

This invention relates to an instrument for the internal flushing or washing of body organs or cavities and is particularly adapted for veterinary practice. The instrument essentially embodies the application of the principle of an injector for removing fluids or solids after they have been broken up and reduced to semi-fluid form, from body organs or cavities by draining or forcing them out through a drainage tube, which for example, may be an uterine catheter, the cannula of a trocar, or stomach tube, or the like, the device being also useful in the application of medicants or anti-ferments to the walls of the cavities or organs, or for the internal injection of purgatives or the like.

Conditions are frequently encountered, particularly in cattle, where feed of one kind or another will ball up into a compact, relatively solid mass within the stomach, resulting in a stoppage or interference with digestion, and a consequent gas formation and swelling, ultimately resulting in death if the condition cannot be relieved. Similar conditions arise in other body organs or cavities which necessitate puncturing and draining, as well as the application of medicines, purgatives and anti-ferments, etc.

It has heretofore been customary to tap the cavity or organ with a suitable instrument, reference here being made to a trocar merely for convenience of description, it being understood however that the description applies equally well to its use with a stomach tube, uterine catheter, or to the cleaning and washing of any body organ or cavity. After the trocar has been inserted and the stylus withdrawn, fluids in the cavity or organ will immediately flow out through the drainage tube or cannula, and if solids are found by feeling with an impaction tube, it is now the custom to break them up as well as possible with the impaction tube, usually some of them coming out of the drainage tube or cannula and the balance being broken up so that it can be digested.

As far as I am aware no one has ever devised an instrument which will insure the immediate removal of the entire mass from the organ or cavity and the complete flush-

ing of the inside wall so that all harmful agents may be immediately and readily removed, it being apparent that under such conditions, the body organs are immediately relieved and the animal will make a quicker and better recovery than heretofore.

The prime object of the invention, therefore, is to produce means whereby a forcible jet of water, medicant or other liquid, may be used in the removal of compacted masses and for the flushing of the walls of a body organ or cavity, the jet being so directed that the pressure will tend to force compacted material toward the mouth of the drainage tube or cannula and will not force such foreign material more tightly into the convolutions of the stomach, for example, or increase the pressure in the stomach to the pain of the animal.

With the general objects named in view, the invention consists in certain novel and useful features of construction and organization of parts as hereinafter described and claimed; and in order that it may be fully understood, reference is made to the accompanying drawing, in which:—

Figure 1 is a foreshortened section taken through a trocar to illustrate the relationship between the stylus and drainage tube or cannula.

Figure 2 is a reduced foreshortened section taken through a cannula with one form of the combined impaction and jet tube in operative relation thereto.

Figure 3 is a similar section to illustrate a modified form of combined impaction and jet tube.

Figure 4 is a section on the line IV—IV of Figure 2.

Figure 5 is a perspective view of the end of the jet tube shown in Figure 2.

Figure 6 is a similar view of the jet tube illustrated in Figure 3.

Figure 7 is a section on the line VII—VII of Figure 3.

In the drawing, where like reference characters identify corresponding parts in all of the figures, 1 represents a stylus terminating at its front end in a piercing point 2 and at its rear end in an operating handle 3, the

operating end being of proper diameter to fit within a discharge tube or cannula 4 equipped with a sharpened front edge 5 and with a flared or any other suitable rear end 6.

5 The stylus and cannula of the character shown in the drawing constitute what is generally referred to as a trocar and is used in piercing an animal body until the front end of the cannula has entered the body organ or 10 cavity to be drained or otherwise treated, the stylus is then withdrawn, and if there is liquid or gas under pressure in the pierced organ, it will frequently partially flow out the drainage or discharge tube as the stylus 15 is withdrawn from position.

The preferred form of the combined jet and impaction tube for the lavage or washing or treatment of the organ, is shown in Figures 2, 4 and 5, said instrument comprising 20 a tubular body portion 7 terminating at its front end in a return bend 8 formed with a jet orifice, the preferred proportion of the parts being such that the jet orifice 8a, when the body of the tube 7 is against the wall of 25 the cannula, will lie in substantial alinement with the longitudinal axis of the cannula, the rear end of the jet tube being equipped with any suitable means 9 for detachable connection with a source of liquid under pressure, 30 such as a city water supply or with a gravity or pressure feed for a medicant, anti-ferment, or the like, depending upon the nature of the treatment to be applied.

In order to center the jet tube in substantial alinement with the bore of the cannula so that the operator may manipulate the tube to attain the best jetting action, and at the same time to avoid as much as possible the clogging or stoppage of the liquid passing 40 out through the cannula, the jet tube is rigidly secured to a guide ring 10 of such diameter as to be slidingly received within the cannula so that the jet tube may be reciprocated to break up a mass within the animal body and 45 to secure the most efficient washing of the material out through the cannula or discharge tube. In order to prevent the accidental projection of the guide ring 10 beyond the front end of the cannula where it might 50 become caught and make it difficult to withdraw without injury to the animal, a stop 11 is secured adjacent the rear end of the tube 7, the stop and guide ring 10 being so positioned that the former will engage the flange 6 of 55 the cannula and prevent the forward movement of the jet tube and ring beyond the dotted line position shown in Figure 2.

With this type of construction it will be evident that the jet orifice 8a will always wash material toward the cannula, and that the return bend construction also offers protection to the jet orifice to prevent clogging or stoppage.

In the construction shown in Figures 3, 65 6 and 7, a modified type of jet tube is illus-

trated, which is particularly useful in breaking up balls of fibrous material, such as hay or hair, said jet tube comprising a body portion 12 having a closed front end 13. The body 12 rearward of its front end is tubular and is provided at its rear end (not shown) with a detachable connection for attaching a source of liquid supply. The front end of the jet tube 12 is provided with a series of rearwardly facing hooks 14 which may be used to catch into a ball of fibrous material for the purpose of tearing it up so that it may be pulled out through the cannula, and to assist in forcing the material toward the mouth of the cannula, and to flush the cavity or organ, a source of liquid supply is connected to the tube 12, the liquid jetting out through the jet orifices 15 formed in certain of the foremost hooks 14, it being evident that the hooks, in effect, form protective housings or hoods for the jets to prevent the clogging thereof when in use, and that the action of the rearwardly jetting liquid is substantially similar as far as flushing is concerned to the construction shown in Figure 2. With this type of construction, the device has some play within the cannula so that its front end can be projected side-wise out of axial alinement with the bore of the cannula, although, it will be obvious that, if desired, the hooks 14 may be made sufficiently wide or long to come into guiding contact with the wall of the cannula and thus maintain the device in substantial alinement therewith.

From the above description it will be evident that I have described and claimed a construction embodying all of the features of advantage set forth as desirable, and it is to be understood that I reserve the right to make all changes falling within the spirit of the invention and without the ambit of the prior art.

I claim:

1. A device of the character described comprising a drainage tube, a liquid supply tube extending through the drainage tube, and a guide bearing a fixed relation to the supply tube and a sliding relation to the drainage tube.

2. A device of the character described comprising a drainage tube, a liquid supply tube extending through the drainage tube, a guide bearing a fixed relation to the supply tube and a sliding relation to the drainage tube, and a stop to prevent projection of the supply tube and guide beyond the front end of the drainage tube.

3. A device of the character described comprising a drainage tube, a liquid supply tube extending through the drainage tube, and rearwardly facing hooks adjacent the front end of said tube, certain of said hooks being formed with rearwardly facing jet openings.

4. An impaction tube having its front end

formed in a return bend terminating in a jet orifice.

5. An impaction tube having its front end provided with a jet orifice, and a tubular guide carried by said tube and adapted for 5 sliding engagement with the bore of a cannula.

10. An impaction tube having its front end provided with a jet orifice, and a guide member secured to said tube and being adapted for 10 sliding engagement with the internal bore of a cannula.

15. A device of the character described comprising a drainage tube, a liquid supply tube extending through the drainage tube and having one end formed in a return bend terminating in a jet orifice, and a guide member for 15 positioning the supply tube within the drainage tube and to maintain the jet orifice 20 in substantial alinement with the bore of the drainage tube.

In testimony whereof I affix my signature.
ERNEST C. PILGRIM.
